UNITED STATES PATENT OFFICE.

CHRISTOPHER C. TRACY, OF BROOKLYN, NEW YORK.

LEAD-PRESS.

SPECIFICATION forming part of Letters Patent No. 439,986, dated November 4, 1890.

Application filed July 11, 1890. Serial No. 358,364. (No model.)

To all whom it may concern:

Be it known that I, CHRISTOPHER C. TRACY, of Brooklyn, in the county of Kings and State of New York, have invented new and Improved Dies for Lead-Presses, of which the following is a full, clear, and exact description.

This invention relates to certain improvements in my new lead-press die covered by my patent numbered 431,295, granted to me July 1, 1890; and the invention consists, principally, in such construction of the press that two dies may be used at the same time, thus doubling the capacity of the press.

The invention also consists in the special construction of the die, all as hereinafter described and claimed.

Reference is to be had to the accompanying drawings, forming a part of this specification, in which similar letters of reference indicate corresponding parts in all the figures.

Figure 1 is a plan view of the die-blocks and dies fitted thereon. Fig. 2 is a sectional elevation of the same on the line x x of Fig. 1, showing portions of a common press. Fig. 3 is a sectional view of one of the dies. Fig. 4 is a broken plan view of the same. Figs. 5 and 6 are perspective views of the core and core-holder, respectively. Fig. 7 shows a modified form of the core, and Fig. 8 shows a modified form of the tip.

A B represent the die-blocks placed between the piston C of the press and the hollow top block D, which contains the lead E and receives the mandrel F in the operation of the press. In the upper surface of the block B are formed two seats B' B' to receive the two dies G G. The block A is formed with a cavity A', which coincides with the cavity or lead-reservoir D' of the top block D, so that the lead has a free passage from the reservoir to the tops of the dies. Between the dies I place a division-plate II with a sharpened edge to divide the lead, so that an equal portion will be directed to each die. The dies G G are at right angles to the direction of movement of the press. By the employment of two dies, as described, two lead products may be made at a single operation, thus doubling the capacity of the press in a given or stated time.

The dies may be of any appropriate construction; but I prefer to use specially-constructed dies, which I will now describe. These dies are for making lead pipe or traps, commonly known as "S-traps," or by the use of hollow cores J, (shown in Fig. 7,) I may cover wire or wire cable or other material with lead. The dies are duplicates of each other, each comprising a casing a, core-holder b, and core c. Each casing a is formed with ports a' a' and provided at the end with a die-tip a², which gages the external form of the product, while the size of the core prescribes the size and form of the interior of the product. The opposite end of each casing is closed by a screw-plug a³ to hold the core-holder and core in place. The core-holder b of the die is hollow to receive the core, and at the front end is formed with the wedge-shaped projections b' b', which reach past the ports a', as shown clearly in Figs. 3 and 4. These projections b' serve to confine at each side of the die the lead directed to that side through its port a', and it will be observed that the projections terminate at their front ends only a slight distance from the inner end of the die-cap a². Thus the lead passing to the cap a² from each side of the die will meet just before entering the cap a², and hence will be caused to thoroughly unite; whereas it might not so unite if prevented from meeting until entering the cap a². A further result of the projections b', or rather the lowermost one, is to prevent the formation, or rather retention, of "dead-lead"—that is, lead banked up at the bottom of the die—by reason of the shoulder formed by the inner end of the cap a² or its equivalent outlet. The lower projection b' therefore, or any equivalent projection, either carried by the core, core-holder, or the case a, occupies the space at the bottom of the die just inward from the shoulder formed by the inner end of the cap a², and thus the lead is directed to the cap a² or its equivalent outlet. In the absence of this provision a certain amount of lead would bank up in the die at the entrance of the contracted outlet, and, becoming chilled, seriously affect the operation. More or less lead is directed to each side of each die G through the ports a'

2
by turning the said dies by means of the toothed segment K and worm K'.

In operation, to make an S-trap or other curved product the dies will be set with the bridge or division-piece H central, so that the flow of lead will be equal on both sides. This produces a straight tube. When this has proceeded a proper distance, the die is turned to the right, which diminishes the flow of lead 5 in the right-hand port and increases it in the left-hand port. This oversupply of lead causes the product issuing from the die to turn to the left, producing a perfectly true curve, and the thickness of lead will be uniform. When the left curve of the product 10 has reached a sufficient length, the die will be turned to the right, which will reverse the curve and produce a product in the form of an S. The radii of the curves will be more or less, according to the suddenness of the 15 turning of the die. If it be turned slowly, the curve will be larger than if the die be turned from right to left or left to right at once. In making a straight pipe the dies will remain central. In case wire or wire cable is to be 20 covered the hollow core will be put in place and the wire to be covered will be threaded through it. In case strips of metal—such, for example, as are used for setting glass in sky- 25 lights or in show-cases—are to be covered with lead, I remove the core and insert a tip like that shown in Fig. 8, the aperture of which tip is of the shape of the strip to be covered. The strip is then passed through the core- 30 holder and the said tip and the press are put in operation, whereupon the lead will be applied firmly to the metal strip, the thickness of the lead covering being determined by the size of the aperture in the tip.

40 The object of making the core and core-holder separable is to enable the cores to be changed without changing the core-holder; but this feature is not absolutely necessary, and is present only with a view to economy.

45 I do not herein claim, broadly, a plurality of dies in presses of this character, as I am

aware of two or more dies divided by a movable dividing gate at the entrance; but in such presses, besides the difficulty of operating the gate in the presence of the pressure of lead, 50 the gate falls short of satisfactory results, owing to the absence of individual control of the lead directed to each die.

Having thus described my invention, I claim as new and desire to secure by Letters 55 Patent—

1. The combination, with a die-block having two seats and a division-plate separating said seats, of rotary dies having two inlets for the material, substantially as described. 60
2. The herein-described die, comprising a case or hollow body having a contracted outlet for the lead and having a projection at the inner end of said outlet for preventing banking of the lead, substantially as described. 65
3. The herein-described dies, consisting of a hollow body or case having a contracted outlet, and having projections therein maintaining a division of the die and extending toward the outlet of the same, substantially 70 as described.
4. The die-block formed with two seats, in combination with two dies fitted in said seats, and the worms K' and segments K for turning the said dies, substantially as described. 75
5. The die G, formed with lead-ports a', in combination with the core and the core-holder formed with the projections b', substantially as described.

6. The die comprising the casing, the core- 80 holder, and the tip, in combination with the core, the ports a' a', and the projections b', substantially as described.

7. The die-casing having the ports a' a', die-tip a², and plug a³, in combination with 85 the die core-holder b, and a core fitted in said core-holder, substantially as described.

CHRISTOPHER C. TRACY.
